ATTORNEYS

UNITED STATES PATENT OFFICE.

CHARLES O. PELLETIER, OF OAKLAND, CALIFORNIA.

FOLDING BED.

1,344,188.

Specification of Letters Patent.

Patented June 22, 1920.

Application filed July 31, 1916. Serial No. 112,273.

To all whom it may concern:

Be it known that I, CHARLES O. PELLETIER, a citizen of the United States, residing at Oakland, in the county of Alameda and 5 State of California, have invented new and useful Improvements in Folding Beds, of which the following is a specification.

This invention relates to folding beds; and has for its object to simplify and improve 10 the construction and operation of such devices.

This object I accomplish by means of an up-ending bed, pivoted horizontally upon fulcrum-supporting members to permit folding movement, said fulcrum-supporting members being carried for movement upon a suitable base or support, whereby to permit the bed to be swung about a vertical pivot or to be transported from place to place, vertically movable legs for the head of the bed to assist the fulcrum-supporting members, said legs being movable up and down by the tilting action of the bed, whereby, when the bed is in folded position, the legs are raised 20 from the floor to permit the fulcrum-supporting members to be moved about, and folding legs for the foot of the bed, said legs being controlled also by the tilting action of the bed, so that the said legs and 25 bed are foldable and extensible coincidentally.

One form which my invention may assume is exemplified in the following description and illustrated in the accompanying drawings, in which—

Figure 1 shows a side elevation of a device embodying my invention, the parts being shown in extended position.

Fig. 2 shows a similar view with the parts 40 in folded position.

Figs. 3, 4 and 5 show detail views of the vertically movable legs at the front of the bed.

In the form illustrated, I have shown a 45 bed-frame 10, having pintles 11 journaled in fulcrum-supporting members 12; the latter being carried for movement upon a suitable support 13. As shown, the fulcrum-supporting members are in the form of 50 brackets secured at their rear ends to a head-frame 14, which latter is pivoted for swinging movement upon a vertical support 15, and thus swinging movement of the said fulcrum-supporting members is permitted, 55 although the same may be otherwise movable as by means of a traveling support. For the latter purpose I show the support

13 supplied with rollers 16, whereby the entire bed may be moved about from place to place. The head 17 of the bed is carried 60 rigidly upon the frame 14.

The brackets 12, it will be noticed, are in the form of cantalivers, being supported at one end only, and for the purpose of lending them additional support I provide each 65 with a vertically movable leg 18 guided at its lower end by means of a pin 19 secured to the bracket and working in a slot 20. The upper end of each leg is guided by a vertical slot 21, through which passes the 70 adjacent pintle 11. To the side-bar of the bed-frame is connected a downwardly extending crank arm 22, having a pin 23 to enter a horizontal slot 24 formed in the leg. the slots 21 and 24 preferably communicat- 75 ing to form an angular guideway.

When the bed-frame is extended the crank pin 23 lies at the rear of the horizontal slot and the pintle 11 is at the top of the vertical slot, and when the bed-frame is raised the 80 pin 23 is moved forwardly to raise the leg so that the lower ends of the vertical slots touch their respective pins.

The brackets 12 have upward extensions 85 at their forward ends, to which are connected links 26, each running to a forward extension 27 on the end of a bell-crank lever 28, the latter pivoted to one of the side bars of the bed-frame near the foot thereof. The front ends of the bell-crank levers 28 have 90 supporting legs 29 fixed to them, and the rear ends of the said levers have foot pieces 30 secured to them. The legs and foot pieces are parallel to each other and are adapted to swing from a right angular position with 95 the frame to substantial parallelism therewith in moving from an extended to a folded position.

In tilting the bed-frame upwardly, the links 26 thrust the bell-crank levers in a direction to fold the foot pieces and legs, and in folded position the foot piece is spaced from the top surface of the bed to allow room for bed clothing. It will be noted that the head-piece 17 and foot piece 30 are 100 in alinement with each other when the bed is in folded position, such an arrangement providing a secure inclosure for retaining the bed clothing in place. The legs 29, at the foot of the bed, occupy, in extended position, 110 a place beneath the bed-frame and help to support the bed-frame intermediately, and, when folded, are projected upwardly in alinement with the side-bars of the frame.

- The front or head legs 18 serve to support the outer ends of the brackets 12 when in lowered position by reason of the crank arm 23 resting on the bottoms of the slots 24.
- 5 When raised, the said legs 18 are in alignment with the side-bars of the bed-frame and clear the floor, so that the bed may be swung on its vertical pivot 15 or moved about on the rollers 16.

- 10 While I have shown and described herein but one form of device, it will be noted, nevertheless, that the same is susceptible of modification and, therefore, many changes in the construction and arrangement of the 15 several parts may be employed without departing from the spirit of my invention as disclosed in the appended claims.

The side bars of the bed-frame 10 carry at either end upstanding supports 31 to receive the mattress springs 32. For counter-balancing the bed frame I employ contractile coil springs 33 connected to the supports 32 and to the brackets 12 below the pivots 11, the latter connection being preferably 25 made with a transverse bar 34 which unites the brackets 12. Such an arrangement will allow the necessary extension and retraction of the springs on tilting the bed, the springs being stretched from one-third to one-half 30 of their length in the movement of the frame from vertical to horizontal position. Such a counterbalancing arrangement does not embody anchorages to any permanently fixed parts and hence the traveling or 35 swinging movement of the bed is not interfered with.

Having thus described my invention, what I claim and desire to secure by Letters Patent is—

- 40 1. In a folding bed having its frame pivotally secured near the head for tilting movement in a vertical plane, head end down, a foot-piece pivotally connected to the outer end of the frame and forming a support therefor, and means operated by the tilting of the bed for folding the foot-piece into position parallel with the bed-frame and spaced therefrom in such a manner as to engage with the bed clothing.
- 45 2. In a folding bed, a fulcrum support, a bed-frame pivoted horizontally thereon, folding legs beneath said bed-frame near the foot thereof, a foot piece at the end of said frame, bell-cranks connecting said legs and foot-piece and pivoted to the side-bars of the bed-frame, and links connecting between said bell-cranks and said fulcrum support and operative to fold said foot-piece and legs coincidentally with the folding 55 of the bed-frame in a manner to cause the foot-piece to inclose the bedding and the legs to occupy a position parallel with the bed-frame and directed away from the head thereof.
- 60

3. In a folding bed having its frame pivotally secured near the head for tilting movement in a vertical plane, head end down, a foot-piece pivotally connected to the outer end of the frame and forming a support therefor, means operated by the tilting of the bed for folding the foot-piece into inverted position parallel with the bed-frame and spaced therefrom in such a manner as to engage with the bed clothing, said foot-piece comprising a frame normally at right angles to the bed frame when unfolded, and arms connecting the same with the bed-frame at points spaced inwardly from the ends of the latter.

4. In a folding bed having its frame pivotally secured near the head for tilting movement in a vertical plane, a foot-piece pivotally connected to the outer end of the frame and forming a support therefor, means operated by the tilting of the bed for folding the foot-piece into position parallel with the bed-frame and spaced therefrom in such a manner as to engage with the bed clothing, said foot-piece comprising a frame normally at right angles to the bed-frame when unfolded, arms connecting the same with the bed-frame at points spaced inwardly from the ends of the latter, and a leg rigidly connected with the inner end of each arm to assist in the support of the bed-frame, said legs being foldable into position parallel with the bed-frame and directed away from the head thereof.

5. In a folding bed, a movable fulcrum support, a bed-frame pivoted thereto, supporting legs for the fulcrum support, said legs having approximately L-shaped slots in their upper ends, means to guide the legs to allow of sliding movement thereof, the pivots of the bed-frame being passed through the vertical legs of the slot, and means to positively raise and lower the legs including projections operating in the horizontal legs of the slots whereby when the bed-frame is lowered, said projections will ride along the bottoms of the horizontal legs of the slots and depress the legs and when the bed-frame is raised the projections will ride along the tops of the horizontal legs of the slots to positively raise the legs, said pivots of the bed-frame acting to engage the ends of the vertical legs of the L-shaped slots so as to limit the vertical movements of the leg both in raising and lowering thereof.

In testimony whereof I have hereunto set my hand in the presence of two subscribing witnesses.

CHARLES O. PELLETIER.
